Des. 196,607
Patented Oct. 15, 1963

196,607

TOOL FOR HANDLING EGGS AND SIMILAR ARTICLES

Edwin R. Hirt, Orinda, Calif., assignor to Food Systems,
Inc., Berkeley, Calif., a corporation of California

Filed Dec. 31, 1962, Ser. No. 73,012

Term of patent 14 years

(Cl. D54—13)

F i g. 1

F i g. 4

F i g. 2F i g. 3FIGURE 1 is a top plan view of a tool for handling eggs and similar articles embodying the new design;

FIGURE 2 is a side elevational view of such tool;

FIGURE 3 is a front elevational view thereof; and

FIGURE 4 is a fragmentary bottom plan view thereof.

The broken-line showing of eggs in FIGURE 2 is for illustrative purposes only.

I claim:

The ornamental design for a tool for handling eggs and similar articles, substantially as shown and described.
